CLAIM

The ornamental design for a skin cream applicator, as shown and described.

DESCRIPTION

FIG. 1 is a perspective view of a skin cream applicator; FIG. 2 is a front view of the skin cream applicator; FIG. 3 is a rear view of the skin cream applicator; FIG. 4 is a left side view of the skin cream applicator; FIG. 5 is a right side view of the skin cream applicator; FIG. 6 is a top view of the skin cream applicator; and, FIG. 7 is a bottom view of the skin cream applicator.

In the drawings, the equal-length broken lines depict portions of the skin cream applicator that form no part of the claimed design.
